STOKER

Edwin Archer Turner, New York, N. Y., assignor
to The Standard Stoker Company, Incorporated,
a corporation of Delaware

Application July 17, 1931, Serial No. 551,378

21 Claims. (Cl. 110—101)

This invention relates to stokers for general application and more particularly in some of its details to stokers especially adapted for use in connection with locomotives both large and small

5 such as road and switcher engines.

It is the general object of the invention to improve and perfect the construction of the elements of a stoker and to provide a new advantageous combination thereof resulting in an improved stoker possessing a minimum of moving or wearing parts compactly positioned so as to occupy but little space on the locomotive and tender and arranged to transfer fuel in a loose state from the source of supply to the fire in a direct route. In carrying out this general object of the invention it contemplates, among other features, the provision of a sectional feed conduit mounted against the underside of the locomotive and tender decks passing fuel from the tender fuel bunker to a distributor at the firing opening in the backwall of the locomotive firebox above the firebox grate, the feed conduit and distributor being disposed wholly beneath and below the plane of the locomotive and tender decks.

20 Another object is to provide in a locomotive stoker of the above characteristics an improved arrangement of rigidly mounted feed conduits so disposed as to permit relative movement between the locomotive and its tender, and one embodying an improved riser fuel casing arranged to receive fuel by power or manual delivery from the tender fuel bunker or other source of supply.

25 These and other objects and advantages of the invention which consist in the combination and arrangement of the parts and in certain features of construction will become apparent from the following description when read in connection with the accompanying drawings in which

30 Figure 1 is a side view of the rearward portion of a locomotive and the forward portion of its tender with some parts in vertical longitudinal section and others in elevation, and with the stoking mechanism therefor shown in similar section;

35 Figure 2 is a plan view of the stoker mechanism shown in Figure 1 with portions of the locomotive and tender shown conventionally;

40 Figure 3 is a section on the broken line 3—3 of Fig. 1 with parts broken away;

45 Figure 4 is a section on the line 4—4 of Fig. 1;

50 Figure 5 is a section on the line 5—5 of Fig. 1;

55 Figure 6 is a view similar to Fig. 1 illustrating a modified form of the invention;

Figure 7 is a view similar to Figure 1, but illustrating another modified form of the invention

especially adapted for use with small or switcher locomotives; and

Figure 8 is a transverse fragmentary section on the irregular line 8—8 of Fig. 7.

The present invention provides a stoker wherein the various units are self contained, easily accessible for making repairs and replacement and in which stoker units are so arranged as to form a part of the general design of the locomotive and its tender or other steam generating device, thereby occupying when installed on a locomotive no space whatever in the cab and a minimum of water space on the tender.

For purposes of description the invention as embodied in three different practical forms will be described and illustrated as applied to a locomotive, but it will be understood that its use is not so limited, inasmuch as it is capable of adaptation to other steam generating devices such for example, as boilers for steamboats and stationary power plants.

On the drawings the locomotive is represented at A, its tender at B and the articulated coupling member therebetween at C. The locomotive is equipped with a frame 10 upon which there is mounted a firebox 11 having a backwall 12 with a firing opening therein at 13. 14 represents the firebox grates and 15 the locomotive cab which is provided with a floor 16. The tender B is provided with the conventional fuel bunker 17 and water compartment 18 mounted upon the frame 19. The fuel bunker has a centrally apertured floor 20 which is sometimes termed the tender deck. This deck is in about the same horizontal plane as the cab deck 16. The fuel is conveyed from the fuel bunker 17 to the firebox 11 by stoker mechanism as hereinafter fully described.

The preferred form of the invention is shown in Figures 1 to 5. Referring to these figures the stoker mechanism as a whole is represented at D. It consists primarily of a locomotive unit E and a tender unit F. The latter unit comprises a trough 21 disposed within a water tight compartment 220 and being rigidly fixed by suitable attachment means, not shown, through laterally extending flanges 22, 22a to the underside of the tender deck 20. The trough communicates with the fuel bunker through the elongated opening 23 of the floor 20. Shiftable plates 24 are mounted between the trough and the floor for controlling the passage of fuel from the bunker into the trough. The trough 21 terminates adjacent the front portion of the tender where it carries a tubular conduit extension 25 extending forwardly to a point on the locomotive beneath the cab deck 55

16. There the tubular extension delivers fuel to the locomotive unit E.

The locomotive unit E comprises a hopper-like riser casing 26 substantially V-shaped in vertical and horizontal cross section, which casing extends forwardly and upwardly from a point adjacent the articulated coupling member C through the firing opening 13 into the firebox 11 where in a distributor member indicated as a whole at 27 5 forms the forward end portion of the casing and is disposed a sufficient height above the grates 14 to permit the fuel to be spread thereover in aerial paths. The firing opening 13 is elongated in order to receive in its lower portion the forward end of 10 the riser casing 26 and to permit through its upper portion the manual firing of fuel from above the cab deck 16. That portion of the opening above the deck is closed by any suitable firedoor represented at 28. The riser casing 26 is provided with 15 a vertically disposed apertured rear wall 29 and imperforate sidewalls 30 and 31 which slope inwardly and downwardly from their top marginal edges to form a substantially V-shaped hopper having an arcuate shaped bottom wall 32. This 20 bottom wall extends forwardly and upwardly from the rear wall 29 in a substantially straight line through the firing opening 13 to the distributor 27, and the sidewalls 30 and 31 extend forwardly and inwardly from the rear wall 29 through the 25 opening 13 to the distributor 27. This construction forms a peculiarly shaped riser casing which may be said to be V-shaped in vertical and horizontal cross section with the vertex of the riser being disposed at the firing opening 13 or within 30 the firebox 11. A flange 33 extending laterally in a horizontal plane from the upper marginal edges of the back and sidewalls of the riser casing provides means to which the deck 16 is attached, forming a support for the cab deck, and at the 35 same time, forms an open mouth 34 in the riser casing normally closed or covered by the deck 16. In other words, the deck constitutes a top wall for the riser casing 26 rearward of the backwall 12. This covering deck is provided with a hinged portion 35 through which access may be had into the riser or through which fuel may be delivered by hand.

An opening 36 is formed in the riser casing backwall 29 to receive the tubular extension 25 50 of the tender unit F. This extension as best shown in Figure 1, projects through the wall 29 into the casing 26. To prevent loss of fuel between the aforesaid parts and to prevent admission of air through the opening 36 a flanged sleeve 55 37 is mounted on the tubular extension 25 and is held in a covering position over the opening 36 by the compression spring 38 which seats against the flange 39 of the extension.

The conveying means for advancing fuel from 60 the bunker to the firebox consists of a screw conveyor 40 which rotates in the trough 21 and a screw conveyor 41 mounted within the riser casing 26. The latter screw is driven from its rearward end by worm gearing consisting of a worm 65 wheel 42 mounted on the screw shaft 43 which wheel is driven by a transversely extending worm 44 coupled at 45 to a shaft 46 of the prime mover 47, and which worm at its opposite side is mounted in a clutch member 48 arranged to engage 70 clutch teeth 49 on a worm 50. This worm drives a worm wheel 51 which transmits power through the joint 52 for driving the trough screw conveyor 40 as will presently appear. A rocker arm 53 is provided to engage or disengage, as may be desired, the worm 50 with the worm 44, and hence, 75

with the prime mover 47. All of the aforesaid gearing is mounted within a gear housing 54 formed integral with the riser casing 26. Suitable covers as at 55 and 56 are secured to the gear housing 54 in positions to permit access to and 5 removal of the gearing.

The screw 40 is driven from its rearward end through gears 57 and 58 mounted within the gear housing 59 formed integrally with the trough 21, which gears are partly held in position by the removable cover 60. Power is transmitted to the gears 57 and 58 through the shaft 61 at its forward end connected to the universal joint 52 mounted on the shaft 62 of the worm wheel 51. Thus, it will be seen both screws 40 and 41 are 10 driven from the common prime mover 47 through gearing arranged to permit the screw 40 to be cut out of operation independently of the conveyor 41. This is desirable because any foreign material in the fuel that is likely to clog the 15 stoker will be confined in the tender unit F, inasmuch as there is no place for a clog to occur in the locomotive unit E. Therefore, it is necessary, should the tender unit F become clogged by foreign matter, to provide such means as heretofore 20 described to place this unit in inoperative relation with the locomotive unit. By so doing the fuel can be fed manually from the fuel bunker into the 25 riser casing through the hinge cover of the deck 16 and the screw 41 utilized to advance the fuel 30 to the distributor 27 which will function to spread the fuel over the fire and thereby make it unnecessary for the stoker operator to do all the 35 work of firing when the tender unit of the stoker is inoperative.

In normal operation, in the preferred form of the invention, fuel from the bunker 17 falls through the opening 23 of the tender deck 20 provided by the slide plates 24 into the trough 21 from which it is advanced by the screw conveyor 40 forward into the riser casing 26 where the fuel falls in loose form and by gravity from the end of the tubular extension 25 directly on to the screw conveyor 41 which then advances the fuel forwardly and upwardly in a substantially straight course into the firebox 11 where the fuel is received by the distributor member 27. This member consists of a rearward arcuate shaped head portion 63 flanged at 64 for attachment to a similarly shaped flange 65 at the forward end 50 of the riser casing 26. The head 63 is cored at 66 to receive a supply of pressure fluid from the supply line 67. The pressure fluid is discharged from the head through any suitable number of nozzles or openings 68 arranged in the arcuate 55 face of the head 63 to issue a fan shaped blast over and above the plate-like extension 69 which as shown is integral with the head 66. The flanges 70 and 71 at the forward end of the riser casing form in effect rearward extensions of the 60 plate 69. These extensions together with the forward end of the riser casing 26 and the distributor member 27 are protected from the fire within the box 11 by the apertured protecting wall 72 formed above the grate 14.

In this preferred form of the invention as heretofore described it will be understood that while the locomotive unit E, and the tender unit F of the stoker mechanism are rigidly secured respectively to the locomotive and the tender, 70 their construction is such as to permit articulation of the parts. Articulation is provided by making the opening 36 in the riser backwall 29 of sufficient size to permit movement of the tubular extension 25 with the tender B. For this same rea- 75

son the riser casing 26 flares laterally at its rearward end.

A modification of the preferred form of the invention is shown in Figure 6. In this form the tender unit of the stoker comprises a trough 80 rigidly secured to the underside of the tender deck 20. The trough at its forward end is connected with a telescoping extensible tubular conduit indicated as a whole at 81. This conduit 10 comprises a rearward section 82 universally connected at 83 with the trough 80, and the forward section 84 universally connected at 85 with the rear wall 86 of a riser casing 87. The conveying means on the tender comprises the rearward 15 screw section 88 and the forward screw section 88a jointed at 89 in the vicinity of the joint 83 of the conduits. This construction permits articulation between the parts of the stoker mechanism of the locomotive and of the tender. The 20 riser casing 87 of this form of the invention differs from that of the preferred form in that the distributor as shown at 90 is disposed rearward of the stream of fuel advanced by the riser screw 91. The distributor head 90 receives pressure fluid 25 from any suitable number of supply lines 90a. This fluid is discharged through nozzles or openings 92 arranged to discharge a fan-shaped blast against the fuel stream across the mouth or front end portion of the riser casing. This end of the 30 casing as in the preferred form of construction is protected from the fire by the protecting wall 72. In all other respects this form of the invention is similar to the preferred form.

Another modification of the invention is illustrated in Figures 7 and 8. This form is particularly applicable to small road or switcher locomotives.

Referring to the aforesaid figures the tender B has a water compartment 100 and a fuel bunker 101 separated by suitable partition plates as at 102. The partition plates guide the fuel in the bunker to the forward end portion thereof adjacent the fuel gate 103. Just rearward of the gate 40 the floor 104 of the tender is apertured at 105 through which aperture fuel falls by gravity into the chute or spout 106. The flow of fuel is controlled by a slidtable plate 107. The fuel passing through the chute 106 is received in the riser casing indicated generally at 108. The chute 106 45 is flanged at 109 for attachment to the floor 20 and it is disposed in a small compartment 110 formed in the front portion of the tender beneath the fuel bunker. To insure free flow of the fuel by gravity from the fuel bunker 101 into the riser 50 casing 108, the chute 106 is disposed at an acute angle greater than 45 degrees from a horizontal plane or the floor 104. The riser casing 108 is 55 fixedly secured to the locomotive A as will presently appear.

60 The lower end portion of the riser casing is made in the form of an open mouthed hopper 111. This hopper extends beneath and surrounds the lower end portion of the chute 106. It flares sufficiently to permit relative movement between the 65 locomotive and tender, and at the same time, to receive all of the fuel from the chute without loss or overflow. From the hopper portion the riser extends forwardly and upwardly into the firing opening 112 in the backwall 113 of the firebox 114. The firing opening is elongated to receive in its 70 lower portion the forward end of the riser casing and to permit through its upper portion manual firing of fuel above the cab deck 115. This deck forms a top wall or cover for the riser casing 75 and is attached thereto by any suitable fastening

means through the lateral flanges 116 extending from the upper marginal portions of the upright walls 117 of the riser casing. The distributor member 118 at the front end of the riser casing may be formed the same as the distributor 27 5 of the preferred form of the invention, and likewise the construction of the protecting wall 119 and the firebox grate 120, may be the same.

In this and the previously described forms of the invention, brackets 121 and 122 secure the forward end of the riser casing to the firebox backwall and the lower end portion of the riser casing is supported from the locomotive frame 123 by any suitable supporting means such as the plate 124. Thus, the riser casing forms a support for 15 its covering floor or cab deck.

As in the other forms of the invention a screw conveyor is employed to advance the fuel through the riser casing. This conveyor is shown at 125 and is driven from its rearward end through suitable gearing at 126. This gearing is mounted within a housing 127 integrally formed with the casing 108 and at one side it is flanged to carry the prime mover 128. In operation of this modification of the invention the fuel from the bunker 129 flows by gravity through the opening 105 controllable by the plate 107 into the chute 106 from which it passes into the hopper 111 of the riser casing 108 where the fuel is then advanced in a substantially straight course through the 30 riser casing into the firebox by the screw conveyor 125 operating at a rate of speed sufficient to prevent accumulation of fuel in the hopper. As the fuel enters the firebox it is received by the distributor 118 which spreads it over the fire 35 in aerial paths as heretofore described in connection with the preferred form of the invention.

Preferably, the riser screw of each embodiment of the invention is inclined at an angle of less than 45 degrees from the horizontal at which 40 angle of inclination the screw will elevate fuel without exterior pressure being applied to the fuel stream.

Those familiar with stokers will recognize that the invention in the embodiments shown represents a highly simplified stoker construction very effective and efficient in operation and one wherein a minimum of moving parts may be employed. It has the advantage of distributing the fuel from a distributor disposed at the firing 50 opening within the firebox combined with the delivery of fuel through the firebox backwall, and with all of the mechanism including the distributor if desired being disposed beneath the locomotive and tender decks or similar decks or firing floors of other steam generating devices. Another advantage is that fuel may be conveyed from the source of supply to the fire in a loose 55 form free from excessive grinding and pulverizing pressures.

I claim:

1. In combination, a firebox provided with a grate and having a backwall and a firing floor extending rearwardly therefrom, a firing opening in said backwall extending above and below 65 said floor, a riser fuel casing, said riser casing being V-shaped in vertical cross section and being located wholly below the plane of said floor and at its forward end extending into said firing opening and terminating above the level of 70 said grate, the sidewalls of said casing converging forwardly and flaring upwardly and its bottom wall sloping forwardly and upwardly to form a casing of less cross sectional area at its forward end than at its rearward end, means in 75

- said casing for forwardly advancing fuel there-through and a fuel receiving opening into said casing above the rearward end of said fuel advancing means and below the plane of said fixing floor.
2. In combination, a firebox provided with a grate and having a backwall and a firing floor extending rearwardly therefrom, a firing opening in said backwall, a riser fuel casing extending into said firing opening and terminating above the level of said grate, that portion of said casing rearward of the firebox backwall being disposed wholly beneath said firing floor, said casing comprising forwardly converging sidewalls, an arcuate shaped bottom wall sloping forwardly and upwardly to form with the sidewalls a casing of less cross sectional area at its forward end than at its rearward end, a transverse rear wall, said firing floor forming a top wall for said casing, a fuel receiving opening in said casing at its rearward end portion, a screw within said casing mounted approximately coextensive with said bottom wall, said fuel receiving opening being above the rearward end of said screw and below the plane of said firing floor, said screw advancing the fuel in a substantially straight course through said casing, and means at the forward end of said casing for receiving the fuel and projecting the same over the firebed in said firebox.
3. In combination, a firebox provided with a grate and having a backwall and a firing floor extending rearwardly therefrom, a firing opening in said backwall, a riser fuel casing inclined upwardly toward the backwall, said casing communicating with said firing opening and terminating above the level of said grate, said casing at its rear portion being of greater cross sectional area than its forward portion and said rear portion being disposed beneath said floor, said floor forming a top covering for that portion of said casing mounted therebeneath, a transverse rear wall for said casing, a main feed opening into said casing through said rear wall, an auxiliary feed opening into said casing through said floor, a screw mounted within and approximately coextensive of said casing arranged therein to advance the fuel therethrough in a substantially straight course and distributing means receiving the fuel advanced through said casing for projecting the same over the firebed in said firebox.
4. In combination, a firebox provided with a grate and having a backwall and a firing floor extending rearwardly therefrom, a firing opening in said backwall, a V-shaped riser fuel casing inclined upwardly toward the backwall, said casing located wholly below the plane of said floor and at its forward end extending into said firing opening and terminating above the level of said grate, said casing comprising forwardly converging sidewalls, an arcuate shaped bottom sloping forwardly and upwardly to form with the sidewalls a casing of less cross sectional area at its forward end than at its rearward end, and a transverse rear wall, said firing floor forming a top wall for said casing, a main feed opening into said casing through said rear wall, an auxiliary feed opening into said casing through said floor, and a feed screw mounted along said arcuate bottom of the casing for receiving fuel from said feed openings and advancing the same forwardly into said firing opening.
5. In combination, a firebox having a backwall and a firing floor extending rearwardly therefrom, a firing opening in said backwall extending above and below said floor, a riser casing inclined upward toward the firing opening and at its forward end opening upwardly in said firing opening and extending rearwardly from said backwall, the greater portion of said riser casing rearward of said backwall being disposed wholly beneath said firing floor, said riser casing at its rearward end being V-shaped in vertical cross section and having laterally extending flanges extending from the upper marginal edges of its sidewalls for attachment to said floor, said floor forming a top wall for the rear portion of said casing and provided with an aperture and a door therefor affording access into said casing, a rearward transverse wall for said casing having an opening therein for the introduction of fuel, and means in said casing for conveying fuel there-through and delivering it into said firing opening.
6. In a stoker for a locomotive having a cab deck and a tender provided with a fuel bin, in combination, a fuel transfer conduit beneath the fuel bin, an upwardly inclined hopper-like riser casing mounted beneath the locomotive cab deck, an opening in the rear wall of said riser casing, a conduit extension communicating at its rearward end with said transfer conduit and extending forwardly and passing freely through the opening in said riser casing rearwall, a flange circumscribing said extension intermediate its ends, a flanged tube slidably mounted on the forward end of said extension between said first named flange and the riser casing rear wall, and a spring seated between said first named flange and said slidably mounted flanged tube for maintaining said flanged tube in contact with said riser casing rear wall.
7. In a locomotive provided with a firebox having a backwall and a cab deck extending rearwardly thereof, a firing opening in said backwall extending above and below said cab deck, a riser casing mounted on the locomotive opening at its forward end through the lower portion of the firing opening, said riser casing having a sloping arcuate base inclined upward toward said firebox, upright diverging sidewalls, a rear wall, an open top and flanges extending laterally from the upper edges of said sidewalls and rear wall for supporting the locomotive cab deck.
8. In a locomotive provided with a firebox having a backwall, a cab deck extending rearwardly thereof, a firing opening extending above and below said locomotive cab deck, a hopper-like riser casing substantially V-shaped in cross section mounted beneath said locomotive cab deck and inclined upward toward said firebox, and means formed with said V-shaped riser casing for supporting the cab deck thereupon, said cab deck forming the roof portion of said riser casing.
9. In a locomotive provided with a firebox having a backwall, a cab deck extending rearwardly thereof and a tender for said locomotive provided with a fuel bin, a stoker including a fuel transfer conduit beneath the fuel bin of said tender, a screw in said transfer conduit, a firing opening extending above and below said locomotive cab deck, a hopper-like riser casing substantially V-shaped in cross section mounted beneath said locomotive cab deck for receiving fuel from said transfer conduit and extending upwardly and forwardly through the lower portion of said firing opening, and means formed with said V-shaped riser casing for supporting the cab deck thereupon, said cab deck forming the roof portion of said riser casing.
10. As a new article of manufacture, a stoker riser casing for a furnace in the form of a unitary

member comprising a sloping arcuate floor portion, said floor portion being substantially straight along the medial vertical plane of the casing, upwardly extending diverging sidewalls, 5 a rear wall apertured for the introduction of fuel to the casing, and flanges extending laterally from the upper edges of said sidewalls and said rear wall, the upper marginal edges of said sloping floor portion and said rear and sidewalls terminating in approximately the same plane.

10 11. As a new article of manufacture, a stoker riser casing V-shaped in vertical and in longitudinal horizontal cross section, said casing being of greater cross sectional area at its rearward end than at its forward end and comprising upright longitudinally extending forwardly converging sidewalls, an arcuate shaped bottom sloping upwardly from its rearward end to form a common vertex with said sidewalls at their forward ends, and an upright transverse rear wall apertured for the introduction of fuel to the casing, the vertical height of said sloping bottom being approximately equal to the vertical height of said rear wall.

15 12. In combination, a firebox provided with a grate and having a backwall and a firing floor extending rearwardly therefrom, a firing opening in said backwall, a riser fuel casing extending into said firing opening and terminating above the level of said grate, the greater portion of said casing rearward of the firebox backwall being disposed wholly beneath said firing floor, said casing being V-shaped in vertical and horizontal cross section, the sidewalls thereof converging 20 forwardly and flaring upwardly and its bottom wall sloping forwardly and upwardly to form with said sidewalls a common vertex at the forward end of the casing, means disposed in said casing for advancing fuel therethrough into said firing opening, a fuel receiving opening into said casing above the rearward end of said fuel advancing means and below the plane of said firing floor and means for passing fuel into said casing through said fuel receiving opening.

25 13. In combination, a firebox provided with a grate and having a backwall and a firing floor extending rearwardly therefrom, a firing opening in said backwall extending above and below said floor, a hopper-like riser casing mounted beneath the plane of said firing floor, said casing being inclined upward toward the firebox and at its forward end extending into said firing opening and terminating above the level of said grate, said casing having upwardly diverging sidewalls 30 and a rear wall, said firing floor forming a closure for the opening in said hopper-like casing rearward of the backhead defined by the upper marginal edges of said hopper sidewalls and rear wall.

35 14. In a locomotive provided with a firebox having a backwall and a firing opening therethrough and a tender for said locomotive provided with a fuel bin, grates in said firebox, a cab deck extending rearwardly from said backwall in a plane above said grates, said firing opening extending above and below said deck, a hopper-like riser casing mounted beneath the plane of said cab deck, said casing being inclined upward toward the firebox and at its forward end extending into said firing opening and terminating above the level of said grates, a screw in said riser casing arranged to convey fuel therethrough, said riser casing having upwardly diverging sidewalls and a rear wall, said firing floor forming a closure for the opening in said hopper-like cas-

ing rearward of the backhead defined by the upper marginal edges of said hopper sidewalls and rear wall, the rear wall of said hopper having an opening therein above the lower end of the screw in said hopper for the introduction of fuel, 5 a fuel transfer conduit mounted beneath the fuel bin of the tender extending forwardly and delivering through the opening in said hopper rear wall and a screw conveyor in said transfer conduit.

10 15. In combination, a firebox provided with a grate and having a backwall and a firing floor extending therefrom, said backwall having a firing opening therein adjacent said floor, a riser casing extending forwardly and upwardly from 15 beneath said floor into the lower portion of said firing opening and terminating above said grate, that portion of said riser casing rearward of the backwall being disposed beneath said floor and that portion within the firing opening being positioned wholly below the extended plane of the firing floor and opening upwardly to discharge fuel in said plane, a screw in said riser casing for advancing the fuel therethrough, the delivery end of said screw terminating at the discharge 20 opening of the riser casing whereby the fuel is advanced by the impelling flights of the screw to the point of emission from the riser casing, and means at the upwardly opening end of said riser casing for distributing fuel in aerial paths over 30 said grate.

25 16. In combination, a firebox provided with a grate and having a backwall and a firing floor extending therefrom, said backwall having a firing opening therein adjacent said floor, a riser 35 casing extending forwardly and upwardly from beneath said floor into the lower portion of said firing opening and terminating above said grate, that portion of said riser casing rearward of the backwall being disposed beneath said floor and that portion within the firing opening being positioned wholly below the extended plane of the firing floor and opening upwardly to discharge fuel in said plane, means in said riser casing for advancing the fuel therethrough, and means at 40 the upwardly opening end of said riser casing subjacent the forward edge thereof and disposed below the aforesaid extended plane acting on the fuel spilling over said forward edge for distributing the fuel in aerial paths over said grate.

50 17. In combination, a locomotive and a tender each having a deck, said decks lying in approximately the same horizontal plane, said locomotive having a firebox provided with a grate and with a backwall having an opening therein above the 55 grate and adjacent the locomotive deck and said tender having a fuel bin above the tender deck, means for transferring fuel from said fuel bin to said firebox including a conduit system positioned wholly below said decks communicating with the 60 fuel bin and opening upwardly in said firing opening above said grate, said conduit system arranged with the point of initial feeding thereto from the fuel bin and the point of final discharge therefrom in the firing opening positioned in 65 approximately the same level, said transferring means also including a screw conveyor in the discharge portion of said conduit system, the extended axis of said screw passing through the discharge opening of the discharge portion of 70 said conduit system, and means at the upwardly opening end of the conduit system for distributing the fuel in aerial paths over said grate.

75 18. As a new article of manufacture, a stoker riser casing for a furnace in the form of a uni-

tary member comprising a sloping arcuate floor portion, upwardly extending diverging side walls, and a rear wall apertured for the introduction of fuel to the casing, the upper marginal edges of 5 said sloping floor portion and said rear and side walls terminating in approximately the same plane.

19. In combination, a firebox provided with a grate and having a backwall and a firing floor 10 extending rearwardly therefrom, a firing opening in said backwall above the level of said grate, a stoker fuel discharge casing extending forwardly from beneath said firing floor into the firing opening and terminating above said grate, that portion 15 of said casing rearward of the backwall being disposed beneath said floor and that portion within the firing opening being positioned wholly below the extended plane of the firing floor and opening upwardly to discharge fuel, a screw in 20 said riser casing for advancing the fuel therethrough, the extended axis of said screw passing through the discharge opening of the riser casing, and means at the upwardly opening end of said 25 riser casing for distributing fuel in aerial paths over said grate.

20. In combination, a firebox provided with a grate and having a backwall and a firing floor extending rearwardly therefrom, a firing opening 30 in said backwall above the level of said grate, a riser fuel casing extending forwardly from beneath said firing floor into the firing opening and terminating above said grate, that portion of said

casing rearward of the backwall being disposed beneath said firing floor and that portion within the firing opening being positioned wholly below the extended plane of the firing floor and opening upwardly to discharge fuel, and means in said 5 casing for forwardly advancing fuel therethrough, said casing opening upwardly through said firing floor and opening rearwardly below said firing floor above the rearward end of said fuel advancing 10 means.

21. In combination, a firebox provided with a grate and having a backwall and a firing floor extending rearwardly therefrom, a firing opening in said backwall above the level of said grate, a 15 riser fuel casing, said riser casing being V-shaped in vertical cross section and extending forwardly from beneath said firing floor into the firing opening and terminating above said grate, that portion of said casing rearward of the backwall being disposed beneath said firing floor and that portion 20 within the firing opening being positioned wholly below the extended plane of the firing floor and opening upwardly to discharge fuel, the side walls of said casing converging forwardly and flaring upwardly, and means in said casing 25 for forwardly advancing fuel therethrough, said casing opening upwardly through said firing floor and opening rearwardly below said firing floor above the rearward end of said fuel advancing 30 means.
